UNITED STATES PATENT OFFICE

159,131

CONDIMENT DISPENSING UNIT

Arthur G. Ball, Los Angeles, Calif.

Application October 29, 1948, Serial No. 149,386

Term of patent 7 years

(Cl. D44—22)

To all whom it may concern:

Be it known that I, Arthur G. Ball, a citizen of the United States, residing in the city of Los Angeles, county of Los Angeles, and State of California, have invented a new, original, and ornamental Design for a Condiment Dispensing Unit, of which the following is a specification, reference being had to the accompanying drawing, forming a part thereof. On the drawing:

I claim:

The ornamental design for a condiment dispensing unit, as shown.

ARTHUR G. BALL.
